UNITED STATES PATENT OFFICE.

BURTON E. KIPP, OF PHILADELPHIA, PENNSYLVANIA.

DESIGN FOR A HINGE.

SPECIFICATION forming part of Design No. 25,663, dated June 23, 1896.

Application filed May 2, 1896. Serial No. 590,037. Term of patent 14 years.

To all whom it may concern:

Be it known that I, BURTON E. KIPP, a citizen of the United States, residing at Philadelphia, in the county of Philadelphia and State of Pennsylvania, have invented a certain new and original Design for a Hinge; and I do hereby declare the following to be a full, clear, and exact description of the invention, such as will enable others skilled in the art to which it appertains to make and use the same.

This invention relates to a certain new and attractive design for desk-lid hinges.

The invention consists in the new and attractive shape or design of hinge substantially as shown in the drawings, and more particularly described and pointed out hereinafter.

Referring to the accompanying drawings, Figure 1 is a top plan view of the new shape

of hinge. Fig. 2 is a side elevation of the 20 hinge.

The characteristics of my new shape or design of hinge reside in the flat plate members or leaves *a* and *b*, with one member having its flat sides on edge or in a vertical plane 25 while the other member has its corresponding faces arranged at right angles to those of the first-mentioned member, or horizontally.

Having thus fully described my invention, what I claim is—

The design for a hinge, substantially as shown and described.

In testimony whereof I affix my signature in presence of two witnesses.

BURTON E. KIPP.
